UNITED STATES PATENT OFFICE.

WILLY ROBERT UHLEIG, OF DRESDEN, GERMANY.

ANGLING GAME REQUIRING PATIENCE AND SKILL.

Application filed April 26, 1927, Serial No. 186,770, and in Germany December 30, 1926.

The invention relates to an angling game requiring patience and skill and which can be used also as tremometer. With this object in view the difficulties of the game must be made similar for every player. This is obtained, according to the invention, by providing for the angling rod a guide by which the different distances from the pins or hooks, which are designed to be angled by a ring suspended from the angling-rod, to the actual supporting point of the angling-rod, remain always the same for all players. The time used by the player for catching a certain number of pins or hooks is counted according to the rules of the game.

The game can be made more or less difficult by the degree of inclination of the pins and by inclining the same to different sides. When the pins are vertical, catching the same with the ring requires the greatest skill.

The pins or hooks to be caught may be stationary or connected with moving figures, for instance fishes, and they may have barbed hooks over which the angling-ring has to be placed so that the figure can be lifted out with the angling-rod.

To make the game still more difficult, the figures to be angled may have a spherical projection on the bearing surface, so that they rotate easily.

The figures to be angled may be visible to the player or contained in a shallow vessel representing a pond and filled with sand which might be coloured, with darkly coloured water or with any other material adapted to hide the figures, and they may be arranged so that only the pins with a barbed hook project. Floating figures, for instance of celluloid, may be used.

Several embodiments of the invention are shown, by way of example, in the accompanying drawing in which

Fig. 1 shows the game in elevation.

Fig. 2 is an end view of the same.

Fig. 3 shows in top plan view, a game with stationary pins.

Fig. 4 shows in side elevation and

Fig. 5 in top plan view, a game with horizontal figures.

Figs. 6 to 11 each show a pin or figure of different shape.

Fig. 12 shows in section and

Fig. 13 in plan view, a playing board of other form of construction.

Fig. 14 shows a playing-board with angling rods for four players.

Fig. 15 shows in side elevation, a figure or pin with spherical surface.

In the form of construction shown in Figs. 1 to 3 the playing board *a* is made of wood, sheet metal or any other suitable material. In this playing-board *a* any desired number of pins *b* are mounted which are inclined to different sides and at different angles. On the board *a* a wire-bow *c* is fixed on which a guide-element *d* is shiftably arranged, in the top end of which at right angles to the guide-bow *c* a thin wire *e* is shiftably mounted which represents the angling rod. From the free end of the angling-rod *e* an angling-ring *f* is suspended by a thin thread *g*. On the playing-board *a* the picture of a meadow *h* or of a pond *i* may be painted or stuck, and in the pond *i* the fishes *k* are painted one for each pin *b* and the numerals which designate the value of the corresponding pin.

In the form of construction shown in Figs. 4 and 5 figures *o* are used, instead of the pins, and which imitate a fish and have a barbed hook, the figures with the hook being made from thin sheet metal bent to the desired shape. The guide-pin *m* for the angling-rod is formed by a figure imitating an angler. The position of the figures to be angled are indicated by contours *p*.

In the base-plate incisions *q* may be made into which the figures are to be stuck for transport or for storing. Several toy-figures are shown in Figs. 6 to 11, and when the game is being played with covered figures, a figure representing a boot (Fig. 10) or a bottle (Fig. 11) may be mixed under the other figures.

In Figs. 12 to 13 a playing-board is shown which consists of a shallow receptacle filled with sand *s*, toy-figures to be stuck into the sand.

The game may be made in any desired size and for any desired number of players.

In playing the game the player grips the angling-rod *e* at the rear end and by moving the rod steadily and by shifting and lifting the same he tries to bring the angling-ring *f* over one of the pins or hooks. As the angling-rod is elastic and consequently oscillates when the hand is not steady, so that the ring vibrates, the time for catching a hook or pin with the ring depends on the

patience, skill and steadiness of the player. From this time used for catching a certain number of pins or figures the steadiness of the hand of the player is judged, so that the game serves, so to say, as a tremometer.

As the game in a simple form of construction can be manufactured at low cost it is adapted to be given away by stores for advertising purposes or the place on the board 10 between the pond and guide bow may be used for advertisements.

I claim:—

An angling game, comprising in combination a playing board, an angling rod, a supporting bow at one end of said board, a

guide element shiftably mounted on said supporting bow and having a transverse bore for said angling rod, pins, toy figures with hooks and with barbed hooks mounted on said board inclined at different angles and 20 to different sides, and a ring suspended at the end of the elastic angling rod and designed to be placed over a pin or hook to catch the same, the time used by a player for catching a predetermined number of pins or figures being measured, the game serving 25 also as tremometer.

In testimony whereof I affix my signature.

WILLY ROBERT UHLIG.
